(57) **CLAIM**

The ornamental design for a cookie package as shown and described.

DESCRIPTION

FIG. 1 is a front view of a cookie package, showing our new design.

FIG. 2 is a rear view of the cookie package of FIG. 1.

FIG. 3 is a right side view of the cookie package of FIG. 1.

FIG. 4 is a left side view of the cookie package of FIG. 1.

FIG. 5 is a top view of the cookie package of FIG. 1; and,

FIG. 6 is a bottom view of the cookie package of FIG. 1. The dash-dot-dash lines depict the boundary of the claimed design and form no part of the claimed design. The dashed lines in the drawings depict portions of the cookie package that form no part of the claimed design.

1 Claim, 4 Drawing Sheets
